CLAIM

The ornamental design for auxiliary lenses for eyeglasses, as shown and described.

DESCRIPTION

FIG. 1 is a side perspective view of the auxiliary lenses for eyeglasses showing my new design in the inoperative position;

FIG. 2 is a side perspective view thereof shown in the operative position;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof, the right side being a mirror image.

The eyeglasses are shown in FIGS. 1 and 2 in broken lines for illustrative purposes only.
